UNITED STATES PATENT OFFICE.

MARTIN CONLIN, OF COLUMBIA FALLS, MONTANA.

SHOE-FASTENER.

1,059,838.

Specification of Letters Patent. Patented Apr. 22, 1913.

Application filed June 9, 1911. Serial No. 632,185.

To all whom it may concern:

Be it known that I, MARTIN CONLIN, a citizen of the United States, residing at Columbia Falls, in the county of Flathead and State of Montana, have invented new and useful Improvements in Shoe-Fasteners, of which the following is a specification.

The invention relates to lacing devices, and more particularly to the class of lacing loops designed for use in connection with fasteners for shoes, corsets, gloves, plackets, and similar articles.

The primary object of the invention is the provision of a lacing device of this character in which the lacings may be pulled and loosened freely and tied in the ordinary manner when drawn tight for the fastening of the article.

Another object of the invention is the provision of a lacing device which is simple in construction, formed with few parts, and that may be readily and easily applied to the article, and also that may be manufactured at a minimum expense.

With these and other objects in view, the invention consists in the construction, combination and arrangement of parts, as will be hereinafter more fully described, illustrated in the accompanying drawings, and pointed out in the claim hereunto appended.

In the drawings: Figure 1 is a perspective view illustrating the application and use of the improved fastener, showing it applied to a shoe. Fig. 2 is an enlarged top plan view of one of the lacing loops. Fig. 3 is a side elevation of the same. Fig. 4 is a plan view of the blank from which a part of the fastener is constructed. Fig. 5 is a side elevation of the stud member. Fig. 6 is a sectional view on the line 6—6 of Fig. 2. Fig. 7 is a side elevation of a slight modification of the invention.

Similar reference characters indicate corresponding parts throughout the several views of the drawings.

Referring to the drawings by numerals, the improved lacing loop is constructed from a single blank 5, the same being of the required length, and is formed with intermediate and outer circular-shaped disks or heads 6 and 7, respectively, the blank being bent to form a closed loop with the

disks 6 and 7 arranged in alinement with each other. The disk 6 is adapted to be spaced from the disks 7, which latter overlap each other, the said disks 6 and 7 being provided with central alining openings, through which is passed a stud or rivet member, presently described.

Interposed between the spaced disks 6 and 7 is a peripherally grooved roller 8, the same being journaled upon the tubular shank 9 of a stud or rivet member, the shank 9 thereof being formed at one end with V-shaped cut-away portions to provide at intervals bendable spurs 10, while at the opposite end of the shank is formed a rounded head 11, the same being adapted to bear against the intermediate disk 6, and the spurs 10 are driven through the shoe upper 12 at the lacing edge thereof, when the said spurs 10 are spread outwardly and clenched against the inner face of the shoe upper, thereby securely mounting the lacing loop upon the shoe.

The blank 5, between the disk 6 and 7, when said blank is bent, presents outwardly bowed guard portions 13, so as to permit the free passage of a lacing cord 14 through the loop for its contact with the roller 8, so on pulling upon said cord, the said lacing loops will be caused to oppose each other, thereby securing a shoe upon the wearer.

The lacing loops may be used throughout the full length of the edges of the upper of the shoe, or may be used in connection with any other article of wearing apparel, or the like, where it is desired to employ a lacing cord.

The blank is preferably formed from sheet metal, and may be selected with particular regard to the color and material of the shoe upper, if desired.

In Fig. 7, there is shown a slight modification of lacing loop, wherein the guard portion 15, at one side of the roller 16, is bent at right angles to the disks in the loop, while the opposite side of the latter is outwardly bowed to permit the free passage of the lacing cord through the loop, as will be clearly obvious.

What is claimed is:

A shoe fastener comprising a strip bent to provide a closed loop, the ends and in-

terminal portion of the strip being provided with a lining perforated enlarged circular-shaped portions, a fastener passed through the perforated portion and adapted to be secured to a shoe, and a roller journaled on the fastener and confined within the loop, the said fastener being provided with a head having a flat inner face engag-

ing the intermediate circular-shaped portion to prevent distorting of the loop.

In testimony whereof I affix my signature in presence of two witnesses.

MARTIN CONLIN.
